UNITED STATES PATENT OFFICE.

CHARLES BINGLEY WEBB, OF HOPKINSVILLE, KENTUCKY.

TRACE-HOOK.

SPECIFICATION forming part of Letters Patent No. 329,108, dated October 27, 1885.

Application filed June 11, 1885. Serial No. 168,381. (No model.)

To all whom it may concern:

Be it known that I, CHARLES B. WEBB, a citizen of the United States, residing at Hopkinsville, in the county of Christian and State 5 of Kentucky, have invented a new and useful Improvement in Trace-Hooks, of which the following is a specification, reference being had to the accompanying drawings.

My invention relates to an improvement in 10 hooks, and is designed to be used more particularly as a connection for the breeching, hip, and back straps with the traces.

The object of the invention is to provide a hook for the purposes mentioned which shall 15 be simple in its construction, cheap to manufacture, strong and durable, and one which may be readily connected or disconnected, and yet will hold the parts securely in position against accidental detachment.

20 With these ends in view the invention consists in the combination, with a frame having an opening, of a hook formed with or connected to said frame and turned back so that its end will be adjacent to or projected into 25 said opening.

The invention further consists in the details of construction and combinations of parts hereinafter fully described, and pointed out in the claim.

30 In the drawings, Figure 1 is a perspective view showing my improved hook applied to the eye of the breeching-straps. Fig. 2 is a perspective view of still another form of hook, the same being adapted and shown as applied 35 to a hip-strap.

In the accompanying drawings, in which like letters of reference indicate corresponding parts in all the figures, A represents the breeching-straps, which are shown as connected by a metal breeching-eye, B, which is provided with a hole or opening, a.

C represents my improved hook, which consists of a frame, D, which is formed with a hole or opening, b. The frame D in this case 45 is formed at its inner end with an extension, e, which is passed through the opening a in the breeching-eye B, and is then turned down upon itself, to prevent the detachment of the hook from the eye.

50 At the opposite end of the frame D is formed a hook, E, which extends upwardly from its point of junction with the frame, and then inwardly, its end being located at a point within the opening b below the upper face

of the frame. The opening b in said frame 55 is of a sufficient size to admit the link of a chain on either side of the hook. It will thus be seen that when said chain is in engagement with the hook it cannot become accidentally detached. The hook in this case 60 connects the trace and breeching-straps, thereby supporting the trace in going downhill, and holding the collar and hames upon the shoulders of the horse in their proper relative positions.

65 In Fig. 2 is shown another form of hook, in which case the frame D is provided with a hole or opening, b, and with an extension bent back so that it will form a hook. The difference between this form of hook and that 70 shown in Fig. 1 lies in the fact that the hook in this case is formed with a head at its inner end, which head is provided with an elongated slot adapted to receive the end of a strap, which may be connected, as shown, by 75 a buckle.

From the foregoing description it will be observed that the chain and trace of a harness are securely held in position without danger of becoming detached, the opening b in 80 the frame being of sufficient length to permit of a link being passed on either side of the front end of the hook E, which end projects into the said opening at the middle thereof and below the plane of the side bars thereof, 85 thus preventing the link from becoming disengaged. I attach importance to the peculiar feature and construction of the hook E, and which is provided with a loop or eye to secure it to a hook or strap.

90 My improved hook is adapted for a variety of uses; hence I do not wish to limit myself to its application to the parts of a harness mentioned.

Having thus described my invention, I 95 claim—

The combination, with the straps A, connected by the eye B, having an opening, a, of the trace-carrier, having an opening, an integral hook, and an extension, e, engaging the 100 opening, as set forth.

In testimony that I claim the foregoing as my own I have hereto affixed my signature in presence of two witnesses.

CHARLES BINGLEY WEBB.
